(57) **CLAIM**

The ornamental design for a bottle holder, substantially as shown and described.

DESCRIPTION

FIG. 1 is a front perspective view of the bottle holder.

FIG. 2 is a rear perspective view of the bottle holder.

FIG. 3 is a front view of the bottle holder.

FIG. 4 is a rear view of the bottle holder.

FIG. 5 is a right view of the bottle holder, it being understood that the left view not shown is a substantially mirror image thereof.

FIG. 6 is a top view of the bottle holder.

FIG. 7 is a bottom view of the bottle holder; and,

FIG. 8 is a front perspective view of the bottle holder in an alternate configuration.
